COMBINED PAIR OF SPECTACLES AND
SAFETY CHAIN THEREFOR

Carolina A. Field, New York, N. Y.

Application February 20, 1951, Serial No. 14,280

Term of patent 14 years

(Cl. D57—1)

To all whom it may concern:

Be it known that I, Carolina A. Field, a citizen of the United States, residing in New York city, county and State of New York, have invented a new, original, and ornamental Design for a Combined Pair of Spectacles and Safety Chain Therefor, of which the following is a specification, reference being had to the accompanying drawing, forming a part thereof, in which:

The figure is a front perspective view of a combined pair of spectacles and safety chain therefor, showing the essential features of my new design in full lines, the portion of the chain shown in broken lines is to be completed like the small links immediately preceding the broken lines.

I claim:

The ornamental design for a combined pair of spectacles and safety chain therefor, as shown and described.

CAROLINA A. FIELD.
